(57) CLAIM

The ornamental design for a lid for a beverage container, as shown and described.

DESCRIPTION

FIG. 1 is a perspective view of one embodiment of a lid of the present invention, the broken lines illustrating a beverage container forming no part of the claimed design;

FIG. 2 is a perspective view of the lid shown in FIG. 1, with a tab portion of the lid illustrated in an opened position, the broken lines illustrating a beverage container forms no part of the claimed design;

FIG. 3 is a top plan view of the lid shown in FIG. 1, with the tab portion illustrated in a closed position;

FIG. 4 is top plan view of the lid shown in FIG. 1, with the tab portion illustrated in the opened position;

FIG. 5 is a perspective view of another embodiment of a lid of the present invention, the broken lines illustrating a beverage container forming no part of the claimed design;

FIG. 6 is a perspective view of the lid shown in FIG. 5, with a tab portion of the lid illustrated in an opened position, the broken lines illustrating a beverage container forming no part of the claimed design;

FIG. 7 is a top plan view of the lid shown in FIG. 5, with the tab portion illustrated in a closed position; and,

FIG. 8 is top plan view of the lid shown in FIG. 5, with the tab portion illustrated in the opened position.
